[57] **CLAIM**

The ornamental design for a ball holder, substantially as shown and described.

DESCRIPTION

FIG. 1 is a side elevational view of a ball holder showing my design;

FIG. 2 is a top view of FIG. 1;

FIG. 3 is a bottom view of FIG. 1; and

FIG. 4 is a view taken along the line 4—4 of FIG. 1. The characteristic feature of my design resides in the tubular construction with flattened lower portion.
